UNITED STATES PATENT OFFICE.

JAMES CLAYTON, OF COVENTRY, ENGLAND, ASSIGNOR TO THE VISCOSE COMPANY,
OF MARCUS HOOK, PENNSYLVANIA, A CORPORATION OF PENNSYLVANIA.

PROCESS OF AND APPARATUS FOR THE SPINNING OF ARTIFICIAL SILK.

1,366,162.

Specification of Letters Patent. Patented Jan. 18, 1921.

Application filed July 8, 1919. Serial No. 309,509.

To all whom it may concern:

Be it known that I, JAMES CLAYTON, a subject of the King of Great Britain, residing at 12 Middlesbrough road, Coventry, 5 in the county of Warwick, England, have invented new and useful Improvements in the Processes of and Apparatus for the Spinning of Artificial Silk, of which the following is a specification.

- 10 My invention relates to the spinning, or twisting, process in manufacturing artificial silk from viscose, or like cellulose solution, according to what is known as the Topham system wherein, in the apparatus at present 15 most usually employed the viscose, or like cellulose solution, is forced through small orifices in stationary nozzles into a setting bath the resultant filaments being passed together under guides in the bath and then 20 over drawing rollers, known as goddets, and thence through funnels into rotating spinning boxes by the action of which spinning or twisting, of the filaments takes place between the ends of the aforesaid funnels and 25 the points at which the filaments leave the drawing rollers, or goddets. The rate of spinning, or twisting, is therefore limited to the speed at which the spinning boxes can be rotated.
- 30 The object of this invention is to effect the spinning, or twisting, operation at a greater rate than has hitherto been attainable and I effect this by causing supplementary spinning, or twisting, to take place from both 35 ends in opposite directions that is, in machines of the type aforesaid, between the point at which the viscose, or like cellulose solution, issues from the jet into the setting bath and the point at which the filaments, 40 or thread, reaches the guide immersed in the bath, as well as between the drawing roller, or goddet, and the end of the funnel as aforesaid. To effect this supplementary spinning, or twisting, I impart to the spindles carrying the nozzles, rotary movement 45 in a direction the reverse of that in which the spinning boxes rotate. This rotation of the spindles is preferably effected by means of a small electric motor in connection with 50 each spindle.

I will describe, with reference to the accompanying drawings, an arrangement in accordance with my invention, but it is to be understood that I do not limit myself to

the precise details hereinafter described 55 with reference to these drawings.

Figure 1 is a vertical section, Fig. 2 a plan, and Fig. 3 a side elevation of so much of an apparatus for the manufacture of artificial silk as is necessary to illustrate the 60 application of my invention thereto. Fig. 4 is a sectional detail hereinafter referred to.

The apparatus illustrated is one in which the spinning, or twisting, devices are arranged in double lines, but it is to be understood that my invention is not limited 65 to apparatus arranged in that particular way.

In the drawing A are the spindles carrying the nozzles *a* through orifices in which 70 the viscose, or like cellulose solution, is forced into the setting bath B. The guides in the bath, under which guides the filaments are passed from the nozzles *a*, are marked *b*. The drawing rollers, or goddets, 75 above are marked C, the rotating spinning boxes are marked D, and the funnels through which the threads pass from the said drawing rollers or goddets, to the said spinning boxes are marked E. These parts 80 are, or may be, supported and arranged, in connection with the various other parts of the apparatus illustrated, in the customary manner and therefore it is unnecessary for me to describe, or illustrate, them further 85 than is needed to explain the application of my invention thereto.

According to my invention I impart to the spindles A, carrying the nozzles *a*, rotary motion in a direction the reverse of 90 that imparted to the spinning boxes D; that is to say, if the spinning boxes D, be rotated in a counter-clockwise direction the rotation of the spindles A, will be in a clockwise direction.

95 For the purpose of thus rotating the spindles A, I have illustrated, (see the section Fig. 4) for each spindle, the rotor, or armature, *f*, of a small electric motor, affixed to the spindle, the stator, or field coils *f*², of the motor, being carried by the casing G, shown as being connected to the part *h* into which the inner end of the spindle A, opens to receive viscose, or like cellulose solution, from the supply pipe H, the said 100 casing G, being provided with a long ball-bearing *g* for the spindle A.

The small motors for driving the spindles

can be supplied with current from the same source as that which supplies the motors which drive the spinning boxes.

What I claim is:-

- 5 1. In the manufacture of artificial silk from viscose, or like cellulose solution, the step of spinning or twisting together in one direction a group of filaments substantially as they are formed, and leading the thus 10 twisted filament group to a collecting member rotated in the opposite direction to impart a further twist to the filament group.
- 15 2. In apparatus for spinning artificial silk from viscose, or like cellulose solution, a setting bath, a rotary spinning nozzle through which a plurality of jets of cellulose solution are introduced into the bath to form a group of filaments twisted together, in combination with a spinning box rotated in opposite direction to the spinning nozzle to impart a further twist to the filament group, and means for leading the filament group from the bath to the spinning box.

3. In apparatus for spinning artificial 25 silk from viscose, or like cellulose solution, a rotary spinning box, a rotary spinning nozzle, an electric motor for rotating the nozzle in a direction opposite to that of the spinning box, and guides for leading the 30 twisted filament group from the spinning nozzle to the spinning box.

4. In apparatus for spinning artificial 35 silk from cellulose solution, a pair of oppositely rotated twisting members for twisting together a group of filaments, a setting bath with which one of said members is associated, and means for guiding the filament group from one twisting member to the other.

In testimony whereof I have signed my name to this specification in the presence of two subscribing witnesses.

JAMES CLAYTON.

Witnesses:

ALBERT BROWN,
ANNIE L. WADE.
